A. G. McGREGOR.

H. G. HODGSON,
PHOTOGRAPHIC PRINT AND PLATE WASHER.

APPLICATION FILED SEPT. 23, 1912.

Patented Aug. 19, 1913.

1,070,711.

UNITED STATES PATENT OFFICE.

ALBERT G. McGREGOR, OF CHICAGO, ILLINOIS.

PHOTOGRAPHIC PRINT AND PLATE WASHER.

1,070,711.

Specification of Letters Patent. Patented Aug. 19, 1913.

Application filed September 23, 1912. Serial No. 721,856.

To all whom it may concern:

Be it known that I, ALBERT G. McGREGOR, a citizen of the United States, residing at Chicago, in the county of Cook and State of Illinois, have invented certain new and useful Improvements in Photographic Print and Plate Washers, of which the following is a specification.

My invention relates to a washer for photographic prints, plates and the like, and the object thereof is to provide a simple and efficient device of this character, capable of thoroughly and effectually washing such prints or plates.

Speaking in general terms, my washer consists of a receptacle with a series of water supply inlets discharging water into the receptacle substantially in the plane of the bottom of such receptacle, with the result that the prints become thoroughly washed especially as the described arrangement of inlets supplies constant streams of fresh water, and when prints are being washed, it prevents such prints from becoming bunched together and from adhering to any part of the receptacle.

In the drawing Figure 1 is a perspective of my print washer; Fig. 2 a plan view thereof; Fig. 3 a detail enlarged section on the line 3—3 of Fig. 2; Fig. 4 a section on the line 4—4 of Fig. 2 and Figs. 5, 6 and 7 detail sections of two modified forms of construction as regards the water supply.

Referring to the present and preferred embodiment of my invention as illustrated in Figs. 1 to 4 of the drawing, the same comprises an inner and outer receptacle, the former having a series of water inlets discharging water along the bottom of the receptacle, and having a series of water outlets at its margin discharging water into the outer receptacle from which the water finally escapes through a single outlet. While this receptacle may be made of any desired shape and dimensions I prefer the circular shape illustrated in the drawing and will describe the same without intention of limiting myself thereto.

As shown in the drawing, the inner receptacle comprises a bottom 1 and a vertical wall 2 while the outer receptacle comprises an outer concentric wall 3 secured to the ex-

tended bottom 1 described, an annular space being thereby provided between the two walls 2 and 3 and such walls being braced in suitable manner as by means of the braces 4. In practice and by preference the bottom 1 is formed in a series of segmental sections each made of sheet metal and adapted to overlap, the same being secured together at such overlapped portions to form a closed bottom except for the water inlets or openings hereinafter mentioned. As more clearly shown in Fig. 3, the overlapped edge of each section is grooved in order to form a radial conduit or water supply passage 5. When these sections are assembled and connected together these conduits communicate at their inner ends with a central water supply chamber 6 secured in suitable manner to said sections. Each conduit is provided with a series of water supply openings or inlets 7 for discharging the water in a direction at right angles to said conduits which are arranged along substantial lines radial of the receptacle, as indicated in Figs. 1 and 2. Moreover these water inlets or openings are arranged to discharge the water all in the same direction and substantially along the bottom of the receptacle. These openings may be formed in any suitable manner and in the present instance I have shown them provided by striking up the overlapping edge of the sections or plates, although the walls of such openings may be separately formed and secured to the sections. Any suitable number of these conduits may be employed but I prefer to use a series of four of them, and likewise any suitable number of water inlets for discharging water into the receptacle may be employed. The bottom is provided centrally with a vertical chamber 8 which communicates at its lower end with the chamber 6 common to all of the conduits. This chamber 8 is provided at its upper end with a nipple 9 for connection with a hose or the like communicating with a suitable source of water supply. The inner receptacle is provided at its margin and at the bottom of its wall 2 with a series of outlets 10 communicating with the annular space between the two walls 2 and 3 from which space the water finally drains through the outlet 11.

The operation of the washer is as follows: The water being supplied through the chambers 8 and 6, flows through all of the conduits 5 from whence the water is discharged and enters the receptacle through the inlets or openings 7. The prints or plates are placed within the inner receptacle and obviously in the path of the fresh water discharged thereinto. Owing to the current of water in the same direction and from a plurality of discharge openings, the prints are kept sufficiently agitated and moreover are prevented from bunching together or clinging to any part of the washer with the result that the prints are thoroughly washed.

If desired the central water chamber 8 may be dispensed with and the water caused to enter the conduits at different points as illustrated in Figs. 5 and 6. In Fig. 5 I have shown the chamber 6 as provided with a depending nipple 6^a to which the hose may be attached and in Fig. 6 I have shown such chamber 6 as provided with a substantially radial supply pipe 12 leading thereto and extending to the outer edge of the washer where its end is upturned to serve as a nipple or connection for the water supply pipe. Particularly when no chamber 8 is used at the center of the washer, as in Figs. 5 and 6, I prefer to give the innermost nozzles or orifices a slight angularity toward the periphery in order to prevent the formation of an eddy or eddy currents at such open center.

In Fig. 7 I have shown a modified form of construction as respects the supply conduits. If desired, these conduits may be made of a plurality of radial pipes 13 arranged in spider form (any desired number of pipes being used) and connected together at their center by a water supply chamber 14. These pipes each have on one side a series of nozzles or orifices 15 of the same character as the orifices or openings 7 and discharge water in a plane parallel with the bottom of the receptacle. The entire spider is preferably removable from the receptacle.

I claim:

50 1. A washer of the class described comprising a receptacle having on its bottom a series of water inlets located above the bottom and discharging water substantially in the plane of such bottom.

55 2. A washer of the class described comprising a receptacle having on its bottom a series of water inlets located above the bottom and discharging water substantially in the plane of such bottom, said inlets being arranged along different lines radial of the receptacle.

60 3. A washer of the class described comprising a receptacle having on its bottom a series of water inlets located above the bottom and discharging water substantially in

the plane of such bottom, said inlets being arranged to discharge in the same direction of rotation.

4. A washer of the class described comprising a receptacle having on its bottom a series of water inlets located above the bottom and discharging water substantially in the plane of such bottom, said inlets being arranged along different lines radial of the receptacle and discharging at right angles to said lines.

5. A washer of the class described comprising a receptacle having on its bottom a series of water inlets located above the bottom and discharging water substantially in the plane of such bottom and also having a water outlet at its margin and substantially in said plane.

6. A washer of the class described comprising a receptacle having on its bottom a series of water inlets located above the bottom and discharging water substantially in the plane of such bottom, and also having a water outlet at its margin, and an outer receptacle receiving such outlet water and itself provided with an outlet.

7. A washer of the class described comprising a receptacle having on its bottom a water supply conduit and a series of water inlets communicating therewith and arranged above the bottom to discharge water substantially in the plane of such bottom.

8. A washer of the class described comprising a receptacle having on its bottom a series of water supply conduits provided with a common water supply, and a series of water inlets communicating with the conduits and arranged above the bottom to discharge water into the receptacle.

9. A washer of the class described comprising a receptacle having on its bottom a series of water passages comprising a central chamber communicating with a source of water supply and a series of radiating conduits provided with openings located above the bottom and discharging water into the receptacle.

10. A washer of the class described comprising a receptacle having a bottom of sheet metal with portions thereof projecting above the plane of the bottom and having openings in position to discharge water substantially in the plane of the bottom and over its top surface, and means for supplying water to said openings.

11. A washer of the class described comprising a receptacle having a bottom of sheet metal with portions thereof projecting above the plane of the bottom and having openings in position to discharge water substantially in the plane of the bottom and over its top surface, said receptacle having side walls provided with water outlets substantially at the plane of the bottom, and means for supplying water to said openings.

12. A washer of the class described comprising a receptacle having a bottom consisting of segmental plates or sections adapted to overlap, the overlapped edge of each section being grooved to form a water conduit and the conduits of all the sections meeting centrally and communicating with a common source of water supply, the over-

lapping edges of the sections providing openings discharging water into the receptacle. 10

ALBERT G. McGREGOR.
